UNITED STATES PATENT OFFICE.

WILLIAM DRAYTON, OF KACHELMACHER, OHIO.

KILN.

960,286.

Specification of Letters Patent. Patented June 7, 1910.

Application filed August 6, 1908. Serial No. 447,841.

To all whom it may concern:

Be it known that I, WILLIAM DRAYTON, a citizen of the United States, and a resident of Kachelmacher, in the county of Hocking and State of Ohio, have invented a new and Improved Kiln, of which the following is a full, clear, and exact description.

This invention relates to certain improvements in kilns adapted for burning brick or other ceramics, and involves a system whereby a plurality of separate portable kilns are arranged in series to form a continuously moving tunnel in which the bricks are first dried, then burned, and finally cooled. Each kiln involves a portable base or truck and a removable open-ended hood or cover, and these separate kilns or units when arranged in series may be continuously moved along a track and new kilns containing green brick added to one end of the series and the kilns containing the burned and cooled brick removed from the opposite end of the series. Each kiln carries its own furnace, and, therefore, the running gear of the kiln is unaffected by the high temperature of the flames and gases of combustion employed in burning the brick. In addition to the kiln trucks and removable hoods, I provide a transfer truck which serves to support the hoods while the kiln trucks are being conducted to the storage chamber and emptied, and which also serves to bodily transfer both the kiln trucks and their hoods from the discharge end of the series back to the receiving end where the hoods may be supported upon the transfer truck while a kiln truck is removed, re-loaded and returned beneath its hood ready for attachment at the beginning end of the series.

Reference is to be had to the accompanying drawings, forming a part of this specification, in which similar characters of reference indicate corresponding parts in all the figures, and in which—

Figure 1 is a top plan view of a system constructed in accordance with my invention; Fig. 2 is a side view thereof; Fig. 3 is a horizontal longitudinal section through a plurality of hoods or tunnel sections arranged in series; Fig. 4 is a vertical section taken longitudinally of a transfer truck and transversely of a kiln truck and hood, the left-hand half of said section being taken on the line 4—4 of Fig. 5, and the right-hand half of said section being taken on the line 4—4^a of Fig. 5; Fig. 5 is an end view of the

transfer truck and parts shown in Fig. 4; Fig. 6 is a horizontal section through a kiln truck, said section being taken on the line 6—6 of Fig. 7; and Fig. 7 is a side elevation of a kiln truck and removable hood, portions thereof being broken away.

Each of my improved kilns, while in use, constitutes one of a series of units going to make up a continuously moving tunnel, different steps of the process taking place in the different kilns as they progress along the series. In the specific form of kiln illustrated in the accompanying drawing, each unit includes a truck serving to support the load of brick, and including a furnace for burning the brick, and detachably supported upon each truck is a removable open-ended hood or tunnel section. Each truck is provided with a brick-supporting surface 75 formed of a plurality of inverted channel-shaped members 10, each having a passage 11 therethrough extending longitudinally of the truck. Adjacent one end of the truck, I provide a transverse distributing chamber 12, communicating with one end of each of said passages 11, and at each end of the distributing chamber is disposed a suitable furnace. The two furnaces come adjacent opposite sides of the car and adjacent the forward end thereof, and include diagonally disposed grate bars 13 and an ash pit 14 therebeneath. One side of the transverse chamber or passage 12 is closed, so that the gases entering said passage must travel 90 lengthwise of the car through the passages 11. The channel-shaped members 10 and the passages 11 terminate a short distance from the end of the car opposite to the furnace, so as to leave a space or passage 15, up 95 through which the gases may pass into contact with the brick. As there is no supporting surface over the passage or space 15 to support brick, it is evident that a vertical passage 17 will be formed extending the entire height of the brick and separating the brick of one car or truck from those of the next adjacent truck.

Directly beneath the inverted channel members 10, I provide shallower inverted channel members 18, which form air passages 19 substantially parallel to and directly beneath the gas passages 11. Each of these air passages 19 is provided with an opening 20 leading to the atmosphere beneath the car at one end of said passage, and at the opposite end of each passage is an

opening 21, whereby fresh air may enter the gas passage 11 adjacent the end of the latter and adjacent the open space 15. The inverted channel members forming the passages may be of any suitable material desired and may be supported in any suitable manner. As shown, I provide a plurality of transverse I-beams 22, extending beneath the channel members and themselves supported upon a plurality of longitudinally-disposed pairs of I-beams 23. Between the members of each pair of I-beams 23, are mounted suitable truck wheels 24, by means of which the entire truck may be transported. Adjacent the ends of the trucks may be mounted any suitable form of car coupler 25, whereby adjacent trucks may be secured together. To prevent the wheels and supporting framework of I-beams from being affected by the heat of the furnace, I preferably provide a layer 25 of mineral wool, asbestos, or the like, beneath each furnace, as indicated in Fig. 7, and may, if desired, provide a second layer 27 between the I-beams 22 and the hollow members supported thereon. The passages through said hollow members serve, to a certain extent, as insulation to prevent the supporting framework being unduly affected by the hot gases in the passages 11, and the flow of air through the passages 19 also aids in maintaining the framework in a cool condition.

Upon opposite sides of the hollow members 10 are solid side members 28 resting directly upon the eye beams 22, and extending across one end of the truck and forming one side of the passage 11 is a solid member 29. The members 28 serve to support the hood, dome or covering, which forms one section or unit of the tunnel. In the specific form of dome, hood or covering shown in the accompanying drawings, I form substantially vertical side walls 30, each made up of hollow tiles or bricks and resting at their lower ends upon the side members 28 of the truck. At the lower edge of each wall I preferably employ a longitudinally-extending base member 31, having a metal reinforcement whereby the base member may be employed for raising the dome or hood clear of the truck. The roof or top of the dome or hood is formed of a plurality of specially constructed brick and cast iron reinforcements and rests directly upon the side walls. The end walls of the hood are entirely open. The roof, as shown particularly in Fig. 5, is formed of a plurality of transverse oppositely-disposed pairs of channel irons 32, each pair of which serves to support depending bricks 33, the lower ends of which are of larger size than their intermediate portions. These depending bricks 33 serve to support bridging bricks 34, and upon the latter and beneath the channel irons are disposed transversely-extending hollow bricks

or tiles 35. A roof constructed in this manner, is extremely rigid and the parts are firmly held against accidental displacement. The edges of the roof may be rigidly secured to the side walls 30 by suitable bolts, which may, if desired, extend entirely down through the side walls into the base members 31 of the latter. As previously stated, the hood or dome rests directly upon the side members 28 of the truck, and the ends of the hood are entirely open. The ends of the side walls and also the ends of the roof may be so constructed that when two hoods are brought into engagement with each other and in alinement, a substantially gas-tight joint will be formed. As shown particularly in Fig. 3, the ends of the side walls are provided with dove-tailed joints and reinforcing and sealing strips 36.

For raising any hood or dome out of engagement with its kiln truck, to permit the latter with its load of burned brick to be moved to a storage place, and also to bodily transport the kiln truck and hood either in a loaded or unloaded condition, I provide one or more transfer trucks substantially as shown in Figs. 4 and 5. Each of these transfer trucks is formed of a framework including oppositely-disposed pairs of I-beams 37, between which are journaled suitable truck wheels 38, and extending transversely of the I-beams 37 are I-beams 39 and tracks 40. The tracks 40 are of such gage as to receive the truck wheels 24 of the kiln trucks, and said tracks extend at substantially right angles to the general direction of the length of the transfer trucks. Mounted upon the transfer I-beams 39 are jacks 41 of any suitable character, and these jacks have their upper ends normally at such an elevation and are so disposed, that they may engage beneath outwardly-extending lugs 42 carried by each hood and rigidly secured to the base members 31 of the latter. The tracks 40 of the transfer trucks are of a length substantially equal to the width of said transfer trucks, and serve to support the kiln truck and permit of its being bodily transferred. During the transfer, the hood 30 may rest directly upon the kiln truck or may be raised out of engagement therewith by means of the jack 41.

For supporting and transporting the kiln, I arrange a track 43 adapted to receive the wheels 24 of the kiln trucks, and of such length that a large number of kiln trucks may be supported thereon in a series. While the kilns are traveling along this track and forming a part of the series, new trucks are continually being added at the receiving end, and others are being taken off from the discharge end. As shown in Figs. 1 and 2, the left-hand end constitutes the receiving end and the right-hand end constitutes the discharge end. Extending transversely of

the track 43 at the receiving end, is a track 44 at a slightly lower elevation, and at the discharge end is a second transverse track 45 also at a slightly lower level. These 5 tracks are of wider gage and are adapted to receive the transfer trucks rather than the kiln trucks. Terminating adjacent the tracks 44 may be any suitable number of tracks 46, along which the freshly-loaded 10 kiln trucks may be brought to the transfer track 44, and beginning adjacent the tracks 45 may be any suitable number of tracks 47, along which the kiln trucks bearing the 15 burned and cooled bricks may be conducted to storage. Connecting the track 44 and the track 45, is a transfer track 48, adapted to receive the transfer truck and having turn-tables 49 and 50 at its intersection with said tracks 44 and 45. Adjacent the receiving 20 end of the track 43, I preferably provide a housing 51, adapted to receive a complete kiln truck and hood, and having transverse sliding doors 52 and 53 for closing the end 25 of the series of trucks. Connected to the housing 51 is any suitable suction fan 54.

In the operation of my improved system, the kiln trucks are loaded with green brick and moved along the track 46. A transfer truck supporting a hood is moved along the 30 track 44 into direct alinement with the track 46 and the kiln truck with its load of green brick is moved onto the transfer truck and beneath the hood. The hood is then lowered onto the kiln truck and the latter with the 35 hood is moved off the transfer truck to the portion of the track 43 adjacent the receiving housing 51. The transfer truck may then be moved along the track 44 to the turn-table 49, and thence along the track 48 40 and past the turn-table 50 to the opposite end of the track 43. Upon opening the sliding door 52, the kiln truck and hood with their load of green brick, may be moved into the housing, the door 52 may then be 45 closed, the door 53 opened, the kiln truck and hood connected to the adjacent one of the series, and the entire series moved along the track a short distance. In the first portion 50 of the series of kilns extending along the track 43 at the receiving end, a drying or smoking process is being carried on. In the center kilns of the series, fires are built in the furnaces and the brick are burned in the usual manner. By the time the kilns 55 have traversed approximately two-thirds of the distance along the track 43, the fires are permitted to go out and fresh air entering through the end of the terminal kiln and through the air passages 19, serves to slowly 60 cool the brick, so that by the time the kilns reach the end of the series, the brick are sufficiently cooled to permit of their being handled. The suction fan 54 creates a forced draft for the furnaces and the gases from 65 said furnaces pass upwardly into the spaces

17 and are uniformly distributed among the brick. Most of the heat from the furnace of one kiln will be applied directly to the brick of the next kiln of the series. The housing 51 serves to prevent the admission 70 of air to the kilns at the receiving end and causes it to flow lengthwise through the series from the opposite end. As each kiln reaches the discharge end of the track 43, a transfer truck is brought along the track 75 45 into alinement with the track 43, and the loaded kiln with its hood is moved onto said transfer truck. The hood is raised out of engagement with the kiln by means of the jack, and the transfer truck may be moved along 80 its track 45 into alinement with any one of the series of storage tracks 47. The kiln truck with its hood is then moved off onto the storage track, and the transfer truck and the hood are moved back along the track 48 85 to the receiving end. It is thus only necessary to provide one transfer truck and only one hood more than is sufficient to make up the series need be provided, although a large number of extra kiln trucks may be provided 90 to give sufficient time for them to be loaded and unloaded at leisure.

Having thus described my invention, I claim as new and desire to secure by Letters Patent:

1. A kiln, including a supporting truck, a furnace carried thereby adjacent one end thereof, passages for delivering the gases of combustion through said supporting surface adjacent the opposite end of the truck from said furnace, and means for admitting outside air adjacent the last-mentioned end of said truck.

2. A kiln, including a truck having a supporting surface, a plurality of passages extending longitudinally of the truck and beneath said surface and opening through said surface at one end thereof, a transverse passage communicating with all of said passages adjacent their opposite ends, and a furnace adjacent each end of said transverse passage.

3. A kiln, including a truck having a supporting surface, a plurality of passages extending longitudinally of the truck and beneath said surface and opening through said surface at one end thereof, a transverse passage communicating with all of said passages adjacent their opposite ends, a furnace adjacent each end of said transverse passage, 115 and air passages beneath said first-mentioned passages and each having one end thereof communicating with the outside atmosphere, and the opposite end thereof communicating with the interior of the kiln.

4. A kiln, including a supporting surface having an opening therethrough adjacent one end thereof, a plurality of passages extending beneath said surface from the opposite end of the kiln, a transverse passage 130

communicating with all of said first-mentioned passages adjacent the opposite end of the kiln, a furnace adjacent each end of said transverse passage, and a detachable 5 dome or hood for inclosing the material upon said supporting surface.

5. A kiln, including a truck having a frame formed of longitudinally-extending beams and transversely-extending beams, 10 wheels journaled within said frame, a plurality of inverted channel-shaped members supported upon said frame and extending longitudinally thereof and forming a supporting surface for the material to be 15 burned, a transverse passage beneath said supporting surface and communicating with the interior of each of said channel-shaped members, and a furnace adjacent each end of said transverse passage.

20 6. In combination, a kiln truck, a removable hood or dome supported thereon, a transfer truck for bodily transporting said kiln truck, and means for supporting said hood or dome upon said transfer truck independently of said kiln truck.

7. In combination, a kiln truck, a dome or hood supported thereon, a transfer truck adapted to support said kiln truck, and means carried by said transfer truck for 30 hoisting said hood or dome out of engagement with said kiln truck.

8. In combination, a transfer truck having car rails extending transversely thereof, a kiln truck adapted to be supported upon 35 said rails, a removable hood or dome carried by said kiln truck, and jacks carried by said transfer truck for hoisting said hood or dome and supporting the latter and permitting the removal of the kiln truck independently of the hood or dome.

9. In combination, a track, a plurality of separable portable kiln sections movable longitudinally of said track, each of said sections including a kiln truck and a separable hood or dome, and means for hoisting said 45 hoods or domes out of engagement with their respective kiln trucks at one end of the track, and returning them to the opposite end of the track, independently of the kiln trucks.

10. In combination, a track, a plurality of separable portable kiln sections movable longitudinally of said track, each of said sections including a kiln truck and a separable hood or dome, and a transfer truck for hoisting 50 said hoods or domes out of engagement with their respective kiln trucks at one end of the track, and returning them to the opposite end of the track, independently of the kiln trucks.

11. In combination, a track, a plurality of separable portable kiln sections movable longitudinally of said track, each of said sections including a kiln truck and a separable hood or dome, and a transfer truck for hoisting 55 said hoods or domes out of engagement with their respective kiln trucks at one end of the track, and returning them to the opposite end of the track, independently of the kiln trucks, said transfer truck being also 70 adapted to return said kiln trucks independently of said track.

In testimony whereof I have signed my name to this specification in the presence of two subscribing witnesses.

WILLIAM DRAYTON.
